ADVERTISING DEVICE ROTATED BY HEAT MOTORS

Filed Dec. 28, 1944

UNITED STATES PATENT OFFICE

2,466,003

ADVERTISING DEVICE ROTATED BY HEAT MOTORS

Louis Casper, Richmond Hill, N. Y.

Application December 28, 1944, Serial No. 570,145

4 Claims. (Cl. 40—40)

1

This invention relates primarily to advertising devices and more especially to devices of this type which include one or more rotatable elements, such as discs, upon which are displayed advertising legends, slogans and/or pictures. In the preferred form of the invention the discs are housed in a container which may be shaped like a bottle, and the discs are rotated by a motor within the container, the motor preferably being operated from a source of heat such as an electric lamp.

One of the objects of the present invention is to provide a device of the type mentioned above of novel and relatively simple construction and arranged in such a manner that various portions of the disc or discs contained therein are successively brought to a viewing position, the moving discs serving also to attract attention to the device.

A further object of the invention is to provide a device of the above type which will operate for an indefinite period and which contains a minimum of moving parts.

A still further object of the invention is to provide a device which, because of its simplicity and minimum of moving parts, will require little or no adjustment or care after once having been assembled.

Another still further object of the invention is to provide means for creating the illusion of a bubbling liquid in the container of the device such as in the neck of the bottle when a bottle-shaped container is employed.

In connection with the above it is a further object of the invention to create the bubbling illusion from the same source of fuel that is employed to operate the disc rotating motor.

The above and still further objects of the invention will be more apparent in the following detailed description of the preferred and one modified form wherein reference is made to the accompanying drawings.

In the drawings, Fig. 1 is a plan or top view of a device constructed in accordance with the present invention;

Fig. 2 is a front view of the device with a section of the casing thereof broken away;

Fig. 3 is a vertical sectional view of the device taken substantially on line 3—3 of Fig. 2;

2

Fig. 4 is a detail view of a modified light and heat reflecting arrangement; and

Fig. 5 is an illustration of the invention wherein the container thereof is box shaped.

5 Referring now to the drawings and particularly to Figs. 1, 2 and 3, the housing or container is indicated in general by reference numeral 10. In the modification of the invention disclosed in these figures, the container is bottle-shaped and has a neck 10a. The container rests on a cushion or gasket 10c which is mounted on a base 10b. The cushion 10c is preferably made of rubber or a like substance.

Secured to the base 10b by screws such as 16 15 is a pair of upwardly extending bearing supports 15 which have at the upper ends thereof bearing 14. Pivotably supported in the bearing 14 in a horizontal position is a shaft or rod 12. The bearing supports 15 are of such length that the 20 shaft is somewhere near the center of the housing when the same is on the base.

Secured to the center of the shaft 12 is a hub 11 which has extending through a radial hole therein a tube 20. The tube 20, preferably of 25 glass, is fixed to the hub 11 and has at the ends thereof bulbs 21, 21a, which also are preferably of glass. The bulbs 21, 21a are hollow and the tube 20 provides a passageway from the interior of one bulb to the other. The ends of the tube 30 20 are sealed into each bulb 21, 21a which are substantially of equal size. The tube and bulbs are arranged in the hub 11 in such a manner that if the bulbs and tube were empty, they would substantially balance one another.

35 Also secured to the shaft 12 adjacent the ends thereof is a pair of discs 22 and 22a. The discs 22, 22a have on the outside faces thereof advertising matter 22b, such as lettering, slogans, and/or pictures, and these are successively 40 brought to a viewing position as they rotate. The manner in which the discs 22, 22a are rotated will be described hereinafter.

The bulbs 21 and 21a and tube 20 have therein a liquid the quantity of which is sufficient to 45 substantially fill one bulb and the tube. The liquid is preferably volatile and may be alcohol or a similar liquid, and may also be colored so that movement thereof from one bulb to the other, in a manner pointed out, may be more readily observed and/or serve to attract atten-

tion thereto. The remaining parts of the tube and bulbs are partially evacuated.

Secured to the base 10b adjacent the left hand central portion thereof by screws such as 16a is a lamp bracket 18 and a reflector 17. The bracket 18 holds a lamp 19 in a horizontal position adjacent the center of the base 10b, as shown in Figs. 2 and 3.

When one of the bulbs 21 or 21a contains more of the liquid than the other, it will be heavier, and since the shaft 12 with its attached elements is otherwise balanced, the bulb with the greater amount of liquid therein will cause the shaft and associated elements to rotate until the heavier bulb is in its lowermost position. Fig. 2 shows the bulb 21a in substantially such a position, and in this position the bulb and the liquid therein are subject to the heating effect of the lamp 19 to a considerably greater extent than the other or uppermost bulb 21 and any liquid that may be contained therein.

Since the liquid in the tube 20 and bulbs 21 is highly volatile and the remainder of the volume thereof is evacuated, a relatively small amount of heat applied to the lowermost one of the bulbs such as the bulb 21a in Fig. 2 will cause the liquid therein to vaporize, bubble or boil. Such action of the liquid increases the pressure in the lower bulb whereupon the liquid is forced therefrom and up the tube 20 and into the uppermost one of the bulbs, such as the bulb 21 in Fig. 2. The ends of the tube 20 extend into the bulbs 21 so that when a bulb is in its lowermost position, the end of the tube thereon is adjacent the bottom of such a bulb. With this arrangement substantially all of the liquid in a bulb in its lower position can be forced therefrom by sufficiently increasing the pressure of the gas in the bulb above the liquid. However, in normal operation of the device this condition may never be reached.

As the liquid from the lowermost bulb, such as 21a in Fig. 2, is forced upward, it enters the uppermost one of the bulbs, such as 21. Some time before the major portion of the liquid has left the lower bulb, the weight of the liquid in the upper bulb will be greater than that left in the lower. This condition creates an unbalance of the shaft 12 with its attached elements and when the unbalance is sufficient to overcome the friction tending to hold the shaft 12 at rest, the same will rotate until the heavier bulb is in the lower position. This bulb with the liquid contained therein is now subject to the heat from the lamp 19 whereupon the direction of flow of the liquid is reversed and the bulb which is at this time in the upper position will soon contain a greater weight of the liquid than the lower one. This will cause the shaft to make another half revolution. The bulbs 21 and 21a will now be back to the position shown in Fig. 2, and such cycle of operation will be repeated as long as heat is supplied from the lamp 19. The bulbs 21 and 21a with their connecting tube 20 in conjunction with the heat from the lamp 19 are what may be termed a heat motor or heat engine for rotating the shaft 12 and its attached elements.

Depending upon a number of factors such as the amount of heat given off by the lamp 19, the degree of vacuum in the tube and bulb system, and the volatility of the liquid employed, the time required for a given amount of liquid to move from one bulb to the other may be varied and hence the number of revolutions of the shaft 12 in a given time may be controlled. The above factors may be such that the shaft 12 rotates one

half revolution at a time and stops for a time between each half revolution or they may be such that the shaft rotates continuously.

If half revolutions at a time of the shaft are desired with definite periods of rest between such half revolutions, a latch may be employed to prevent oscillation of the shaft between each half revolution. The latch may take the form of a light leaf spring, such as 31, Figs. 2 and 3, mounted on an arm 32 of one of the bearing supports 15 in such a manner that the end of the spring is in operative relation with projections 33 on the periphery of the adjacent disc 22a. The inertia of the shaft 12 with its associated elements is sufficient to rotate the heavier bulb slightly beyond dead center, to a position such as that shown in Fig. 2, and in such a position the end of the leaf spring 31 engages a projection 33 on the disc 22a to prevent reverse rotation of the shaft and disc. The latch also insures rotation of the shaft 12 always in the same direction.

If faster rotation of the shaft 12 is desired than can be obtained from the employment of one set of bulbs and a connecting tube, more sets may be employed. For example, if two sets were employed and their connecting tubes 20 placed at right angles, there would be, other things remaining the same, approximately twice the rotative force applied to the shaft 12.

Secured to the container or housing 10, either on the inside or outside thereof, on the surfaces that are in planes parallel to the plane of the discs 22 and 22a, are masks or labels 23. Of course, if the container 10 has rounded or oval sides, the masks 23 are on the wide portions thereof. Curved slots or transparent portions, such as 23a, in the masks permit portions of the discs 22, 22a to be viewed therethrough and as the discs rotate the advertising matter thereon in the corresponding ring is observable.

When it is desired that the advertising matter on the discs 22, 22a move from right to left, the slots 23a in the mask on the side of the casing 10 should be above the center of the shaft 12 where the disc appears to rotate in a counterclockwise direction and below the center on the side where the disc appears to rotate in a clockwise direction. However, if the shaft rotates intermittently half a revolution at a time and at such a rate that would make reading or observing the display or the discs difficult, there may be slots 23a both above and below the center of the shaft 12 in both masks, in the manner shown in Figs. 2 and 3. Obviously, where one mask has a plurality of slots each is a different distance from the axis of the shaft 12 so that a ring of printing, for example, on a disc 22 will be observable only through its associated or respective slot 23a.

In order to further attract attention to the device of the present invention, and particularly when the entire device is shaped substantially like a bottle, a bubbling effect in a particular part thereof, such as in the neck, is produced so as to represent a bottle of sparkling or bubbling liquid. This bubbling effect is obtained by a pair of stationary bulbs 24 and 26 connected by a tube 25. The tube and bulb set is stationary within the container 10 and is held in place by a clamp 29 on one of the bearing supports 15 engaging the tube 25. The lower bulb 24 is located so as to be affected by the heat from the lamp 19 and the upper bulb is located in the neck 10a of the housing. An amount of liquid is placed in this set to substantially fill the lower bulb 24, and the tube 25, and to approximately half fill the upper bulb

26. The liquid is preferably a highly volatile liquid, like that in the other tube and bulb system, and the stationary system is partially evacuated. The liquid in the stationary system may also be colored to simulate a beverage.

When the liquid and lower bulb 24 are heated by the lamp 19, the liquid vaporizes or boils, and since the end of the tube 25 extends into the lower section of the bulb 24, the vaporization of the liquid will force the same up the tube 25. As the warmer liquid moves up the tube 25, due in part to the effect of the heat from the lamp 19 on the liquid in the lower end of the tube, the liquid will vaporize in the tube and form bubbles therein. The bubbles will rise in the tube and on entering the upper bulb 26 will agitate the liquid therein and in this manner cause the liquid to simulate a bubbling liquid. The cooler liquid from the upper bulb 26 will flow downward along the inner wall of the tube 25 as the vaporized bubbles pass upward.

In order to concentrate the heat from the lamp 19 on the lower bulb 24 of the stationary set and to minimize the amount of heat that the descending bulb of the rotatable set is subjected to, a shield such as 28 may be employed. This shield is attached to one of the bearing supports 15 and the inside thereof may have a reflective surface so as to reflect some of the heat from the lamp toward the ascending one of the rotatable set of bulbs.

The reflector 17 around the lower part of the lamp 19 in addition to reflecting the heat from the lamp toward the lower bulb 24 of the stationary set and the ascending one of the rotatable set, also reflects the light from the lamp to illuminate the outer surfaces of the discs 22, 22a. Furthermore, light from the lamp 19 also to a considerable extent illuminates the upper bulb 26 of the stationary set to enhance the attractiveness thereof.

Air is allowed to circulate through the device so as to prevent it from becoming overheated. The air enters the device through holes such as 10d of suitable size and number in the base 45 10b and escapes by means of an upper vent such as the hole 10 of Fig. 1 in the cap.

In the modification of the invention shown in Fig. 5 the casing of the device is boxlike. Here the casing is indicated by the reference character C and in substantially all other respects the modification may be constructed substantially like that of Figs. 1 to 3. In the modification of Fig. 5 the stationary set of bulbs 24 and 26 may be dispensed with or, if desired, a picture or other representation of a bottle may be placed on the mask 23 and the upper bulb 26 of the stationary set located in any part thereof.

From the above it is evident that an attractive and novel display device is provided which may represent a bottle or any other article. Such a display device has many advantages over those known heretofore, and it is obvious that various modifications thereof can be made without departing from the spirit or essential attributes of the invention, and it is desired, therefore, that only such limitations be placed thereon as are set forth in the appended claims.

What is claimed is:

1. In a device of the type described, said device including a casing or container having therein a rotatable means, means including a heat motor for rotating said rotatable means, an electric lamp also within said casing for furnishing heat for said heat motor, said rotatable means

including one or more discs having advertising matter on the faces thereof, one or more viewing windows or slots in said casing for viewing successive segments of the advertising matter on the faces of said discs as they rotate, a reflector adjacent said lamp and means including said reflector for reflecting light from said electric lamp to the faces of said discs and heat to said heat motor.

2. In a device of the type described, said device including a casing or container having therein a rotatable means, said rotatable means being impelled by a heat motor operating by the heat from an electric lamp, said rotatable means including a pair of spaced apart dislike members on either side of said heat motor with lettering or pictorial illustrations on the faces thereof, one or more viewing windows or slots in the front and back of said casing in line with the lettering or pictorial illustrations on said discs whereby successive portions thereof are observable as said discs are rotated by said rotatable means, a reflector adjacent said lamp and means including said reflector and said electric lamp for directly illuminating the faces of said discs and reflecting heat to said motor.

3. In a device of the type described, said device including a casing or container having rotatable means therein, said rotatable means including a hub mounted on a shaft supported within said container, one or more tubes supported by said hub and rotatable therewith, each of said tubes having a bulb attached at each end thereof and diametrically located with respect to said shaft, 35 a volatile liquid contained within each of said tubes and their attached bulbs, an electric lamp contiguous to one of said bulbs at a time in the lower section of the path of movement thereof as said shaft rotates, means including the heat from said lamp to cause said volatile liquid to rise to the upper bulb of a pair and thereby cause said upper bulb to outweigh the lower bulb whereupon said overweighted bulb rotates to a position contiguous to said lamp, a pair of discs integral to said hub on either side of said tubes and bulbs, said discs having lettering or pictorial markings thereon, one or more windows or viewing slots in said casing, said slots in viewing position and in line with the lettering or pictorial markings on said discs where said markings are observable through said slots as said discs rotate through the medium of said rotatable means and means to prevent rotation of said discs in one direction, illuminating and reflecting means in said container for directly illuminating said lettering or pictorial markings on said discs, said illuminating means comprising said electric lamp within the container.

4. In a device of the type described, said device including a casing or container having rotatable means contained therein, said rotatable means including a heat motor operated by the heating effect of an electric lamp also within said container, said rotatable means having rotatable therewith and at the sides of said heat motor a pair of dislike members upon which lettering or pictorial markings are inscribed on the flat surface thereof, openings or transparent sections in the shell of said container through which said markings on said dislike members may be viewed, a glass tube mounted in said casing having a glass container at one end thereof contiguous to said electric lamp, a glass container at the other end of said tube, a volatile liquid 75 in said tube and containers, said volatile liquid

being caused to expand and vaporize by the heat from said lamp, and causing thereby said volatile liquid to flow to said glass more remote from said lamp and produce a bubbling effect in said remote container, a light and heat reflector adjacent said lamp and means including said reflector for directing light from said lamp to said bubbling volatile liquid and said lettering or markings on said dislike members and heat from said lamp to said heat motor and the said container contiguous with said lamp.
